ATTORNEY

UNITED STATES PATENT OFFICE

108,115

DESIGN FOR A BROOCH OR SIMILAR ARTICLE

Fulco di Verdura, New York, N. Y., assignor to Paul E. Flato, New York, N. Y.

Application November 27, 1937, Serial No. 73,217

Term of patent 3½ years

To all whom it may concern:

Be it known that Fulco di Verdura, a citizen of Italy and resident of New York city, in the county of New York and State of New York, has invented a new, original, and ornamental Design for a Brooch or Similar Article, of which the following is a specification, reference being had to the accompanying drawing forming part thereof, in which,

Fig. 1 is a front elevational view of a brooch embodying my design; and

Fig. 2 is a side view thereof.

I claim:

The ornamental design for a brooch or similar article substantially as shown.

FULCO DI VERDURA.
